UNITED STATES PATENT OFFICE.

CHARLES F. HUNTOON, OF CHICAGO, ILLINOIS.

BRAKE HEAD.

Application filed April 5, 1920. Serial No. 371,502.

To all whom it may concern:

Be it known that I, CHARLES F. HUNTOON, a citizen of the United States of America, and a resident of Chicago, county of Cook, 5 and State of Illinois, have invented certain new and useful Improvements in Brake Heads, of which the following is a specification.

This invention relates to brakes for vehicles and more particularly to means for securing the brake-hanger to the brake-head on brakes used for railway cars.

In the use of brake-heads constructed as heretofore extensively employed, the brake-shoes are frequently lost by reason of the brake-shoe key working out in service, especially when the cars are turned upside down, as for instance on coal tipples. This leaves the hanger link free to swing out of the brake-head groove, with the result that the brake-beam drops down on the track. Several forms of clips, or wedge keys have been used in the brake-head grooves in front of the hanger with a view to holding the 20 hanger in place even when the shoes are lost, but such means have proven unsatisfactory, both in point of dependability and simplicity of construction. Such keys are easily lost, and in any event, loose or detachable parts 30 should always be avoided if integrally formed or non-detachable means can be devised to answer the purpose. I propose to do away entirely with the extra parts required for securing the hangers to the heads, 35 as heretofore constructed, and instead of such means I provide integral lugs cast on the brake-heads.

The main objects of the invention are to overcome the liability of brake-hangers becoming disengaged from the brake-head as heretofore used, especially when the cars are tilted or turned upside down in dumping, as required in certain kinds of freight service; to provide an improved and simplified 45 form of brake-head and hanger fastening of this general character adapted both for interchangeable connection of brake-shoes and for ready connection and disconnection of the hanger in such manner as to preclude dropping of the brake frame, even when the 50 brake-shoes are lost; and to provide in the brake-head an open-mouthed hanger slot having one or more projecting lips of similar but more or less irregular or serrated character adapted to prevent disconnection of

the hanger link without first disconnecting the latter from its support.

An illustrative embodiment of this invention is shown in the accompanying drawings, in which—

Fig. 1 is a side view of my improved brake-head and its hanger in their normal operative position with respect to the truck frame, brake-shoe, key and car wheel, the shoe, key and wheel being indicated by dotted lines.

Fig. 2 is a face view of the brake-head and hanger in the position shown in Fig. 1, but with the brake-shoe removed.

Fig. 3 is a fragmentary view of the slotted 70 part of the brake-head as shown in Fig. 2, but with the hanger in its initial stage in the process of assembling on the brake-head.

Fig. 4 is a similar view, with the hanger shown in its second stage of assembling. 75

Fig. 5 is another similar view with the hanger in its third stage of assembling, ready for swinging back to its normal operative position.

In the construction shown in the drawings 80 the brake-head 1 is pivotally connected to the brake-hanger 2 and is swingably supported thereby. Said brake-hanger in turn is connected pivotally to and supported by the truck frame 3 or a suitable lug thereon. 85

Said brake-head is provided on its active side or face with an interchangeable shoe 4 secured in place by a locking pin or brake-shoe key 5. Said brake-head 1 is urged forcibly against the wheel 6 by the brake-beam 90 7, as usual in such devices and as will be understood by those skilled in the art without further illustration or description.

The brake-hanger 2 is U-shaped, the connecting part 8 at the lower end serving as 95 a pivot for the brake-head and the upper ends of the arms 2' being provided with ring-shaped tips 9 to receive the pivot bolt 10 carried by the said frame 3.

The face of the brake-head is provided 100 with a transverse horizontal slot or groove 11 adapted to receive the pivot part 8 of the hanger 2. In order to prevent accidental withdrawal of the hanger 2, as by direct outward swinging from said slot, the lips 105 of said slot are formed or provided with my improved stop means, namely, a plurality of shoulders or lugs 12, one on each side in staggered relation, each extending part way across the mouth of the opening 110

and so arranged and spaced that the hanger may be inserted between them as will be explained.

In the form shown in Fig. 2 these lugs 5 12 are of oblong, rectangular shape and each 10 extends about one-third or somewhat less than half of the way across the face of the brake-head; but in the form shown in Fig. 6 the hanger retaining lugs are of triangular 15 shape as viewed from the front, and each extends substantially the full length of the slot, tapering in opposite directions, as at 13.

In order to assemble the device, the hanger 20 may be inserted sidewise with the arms 2' nearly perpendicular to the face of the 25 brake-head, and the hanger is moved first in one direction and then in the opposite direction, so that the leading arm may follow the more or less tortuous trend or curvature of the mouth aperture or slot past the 30 plurality of retaining lugs, after which it may be swung to its normal supporting position, as when the brake-head is mounted in due relation to the truck frame and wheel. 35 The hanger may then be connected to said frame, the arms being well out of registry with the slot opening between the lugs 12. The brake-shoe is then applied, whereupon the 40 brake is ready for use. It is apparent that displacement of said hanger respecting said lugs is impossible without disconnecting the hanger at 9 and swinging it to a position nearly at right-angle to the face of the brake-head, so as to register with the mouth of 45 the groove 11.

With the form shown in Fig. 6 the hanger may be dropped directly into the slot when turned to bring its middle part into parallel relation to said slot, as shown by dotted 50 lines. It may then be secured by swinging it so that said part will be perpendicular to the main axis of the head 1 and will lie partly under the triangular lugs 13, as shown by full lines, in which position it is hung 55 when in use, as will be understood by comparison with Fig. 2.

While I have chosen to show a pair of lugs in each of the specific illustrations, my invention is not limited to any particular number of lugs, though I prefer a symmetrical arrangement of parts. 50

Although but two specific embodiments of this invention are herein shown and described, it is to be understood that some of the details of the constructions shown may 55 be altered or omitted without departing from the spirit of the invention as defined by the following claims, and that the features of primary importance are common to both forms. 60

I claim:

1. A slotted brake-head adapted for interchangeable hangers, said brake-head having a distorted mouth for the slot with a pair of mutually spaced lip lugs overhanging the 65 slot, one on each side of and adjacent to the ends of the slot to normally retain the hanger therein, said slot being wide enough to provide side clearance and play for said hanger as great as the overhang of said 70 lugs.

2. A device of the character described comprising a brake-head having a slot therein, in combination with a brake-hanger having a part disposed longitudinally in said slot and normally secured therein, said 75 brakehead having a plurality of lugs overhanging said slot on opposite sides thereof and in staggered relation to hold said part in place against transverse movement thereof, said slot as a whole being wider than said hanger part to provide for limited sidewise play, and the openings between the several lugs and the opposite walls respectively being large enough to admit a side member of 85 the hanger for the admission and removal of said hanger part without appreciable tilting or swinging of said hanger on its said part as an axis. 80

Signed at Chicago this 2nd day of April, 90
1920.

CHARLES F. HUNTOON.
